UNITED STATES PATENT OFFICE.

EMANUEL B. ADLER AND JEROME ADLER, OF PITTSBURGH, PENNSYLVANIA.

HEATING STOVE.

Application filed November 23, 1921. Serial No. 517,204.

To all whom it may concern:

Be it known that we, EMANUEL B. ADLER and JEROME ADLER, citizens of the United States, residing at Pittsburgh, in the county 5 of Allegheny and State of Pennsylvania, have invented certain new and useful Improvements in Heating Stoves, of which the following is a specification.

This invention is for an improvement in 10 stoves, and particularly gas stoves of the type having an open front designed to emanate radiant heat.

Stoves of this general type are well known, and are in extensive use at this time. As 15 now generally made, they comprise a back wall made of a thick mass of fire clay in the front, and at the bottom of which, are a plurality of burners. In front of the back wall, and arranged over each burner, 20 is a mantle in the form of a vertical cylinder which is made up of two semi-circular parts, cemented or otherwise secured together. The rear part has a solid wall from which project a plurality of integral points 25 arranged to be heated from the burner and become incandescent. The front section has an open grille of ornamental design, through which the flame from the burner and incandescent parts of the back wall are visible, and through which heat may radiate. 30 Both sections are made from some refractory earthy material, and are very fragile, so that they cannot be handled or shipped without great loss through breakage. Furthermore, 35 they are expensive to make and assemble. The back wall of the stove, being formed of a heavy mass of fire clay, absorbs and retains a large amount of heat.

The present invention has for its principal objects to provide an improved stove 40 which may be more cheaply and easily made, and in which the mantles can be produced of metal rather than refractory material, and are formed as a unit rather than as a 45 series of individual cylinders, as heretofore used.

These and other objects are attained by the novel construction and arrangement of parts hereinafter more fully described in 50 connection with the accompanying drawing, in which:

Fig. 1 is a front elevation of the stove;

Fig. 2 is a vertical transverse section on line II-II of Fig. 1;

Fig. 3 is a horizontal section on line III-III of Fig. 1;

Fig. 4 is a front elevation showing a part of the stove removed;

Fig. 5 is a perspective view of a portion of the stove showing a sheet metal plate 60 which is used to provide points adapted to be heated to incandescence;

Fig. 6 shows in perspective the manner in which the plate shown in Fig. 5 is used;

Fig. 7 shows in perspective a modification.

In the drawing, A indicates a single casting which forms the main part of the stove structure. The casting provides a back wall 5, forwardly extending sides 6, legs 7, vertical cover plate 8, and a horizontal base 9 joining the top of cover portion 8 and the base of the back wall 5. The back wall 5 has a forwardly extending portion 10 along the top thereof, which portion in turn has a 75 rearwardly inclined coping 11. The front face of the back wall 5 is preferably provided with a series of vertically extending spaced apart ribs 12. Between the ribs, the back wall is preferably formed with a 80 plurality of holes 13 therethrough arranged according to a predetermined design. In the base portion 9 is a series of holes 14, one hole being positioned centrally between each pair of ribs and only a short distance 85 in front of the back wall. Rear legs 15 may also be cast integrally with the piece A.

Disposed beneath the base 9 is a burner tube 16 of the shape shown, at one end of which is a mixer 17, and on the top of which 90 are a plurality of burner jets 18, one jet for each opening 14.

The front cover plate for the front of the stove comprises a single casting B. This casting is approximately as long and as high 95 as the vertical back wall 5, the front surface of which it substantially covers. It is preferably in the form of a plurality of integral, vertical, semi-circular columns 20 having an ornamental grille therein. Between the 100 semi-circular parts and projecting inwardly, are ribs 21 adapted to register with a seat upon ribs 12 on the back wall. The cover plate B is held against the back wall in any suitable way, as by bolts passing through it 105 and the back wall. The bolts are indicated at 22. This construction provides in effect a series of separate vertically extending hollow columns or flues having a burner jet disposed centrally of the bottom of each 110 column, the fronts of the columns being open.

In order to provide projections on the interior of the columns, which will be sufficiently small to become incandescent when the burners are lighted. We preferably employ a metal sheet 23 having outwardly struck points 24 thereon. The points are struck in a predetermined position corresponding to the position of the holes 13 in the back wall. This sheet is bolted to the rear face of back wall 5, with the points projecting through the openings 13 in the back wall. The ends of the points will project but a slight distance into the hollow columns, and being formed of relatively thin sheet metal may quickly be heated to incandescence.

This arrangement is cheaper and better than casting small projections on the back wall because of the difficulty of flowing the cast metal into such fine recesses when casting them, although it may be done, as indicated in Fig. 7, in which 5' is a back wall having integral points 24' cast thereon. Furthermore, after being used one or two seasons, the points may burn off, and by providing replaceable sheets, a new sheet can be easily substituted when the points are burned.

The back wall, front cover member, and projections are all coated with a fireproof white paint, which will add to the appearance of the stove, giving it the appearance of being formed of a heat resistant earth, the coating also serving to increase the radiation and reflection of light and heat, and to protect the parts from burning and oxidization.

A sheet metal casing 25 may be provided for enclosing the back. This adds to the appearance of the stove and provides a flue at the rear of the back wall where cold air, entering at the bottom, will rise and contact with the back wall and be heated, passing out the perforated top.

The forwardly extending top portion 10 serves to throw the heat outwardly, while portion 11 is provided primarily for ornamental purposes to partially close the top of the stove and give it a finished appearance.

A stove constructed as herein described can be produced commercially, cheaply and easily. The cast iron front cover can be made much more cheaply than the clay or earthy mantles heretofore used, and the same degree of care in using it is not necessary. There are but few parts, and all are readily accessible.

Various changes in the details of construction and arrangement are within the contemplation of our invention.

We claim:

1. A stove comprising a back wall member, a front cover member secured to the front of the back wall, one of the members

having vertical portions integral therewith for providing a series of separate flues between the front cover and back wall, and a burner at the lower end of each flue.

2. A stove comprising a back wall member, a front cover member secured to the front of the back wall and comprising an integral member having a series of vertical grilles therein, means for spacing the front cover member and back wall from each other and providing a plurality of separate vertical flues between the front cover and back wall, and a burner having a series of jets thereon, one of the jets being disposed at the bottom of each vertical flue.

3. A stove comprising an integral cast iron member forming the back wall, sides and base, a cast iron front member secured in front of the back wall and having grilles in the front thereof, integral means on one of said members for maintaining them in spaced relation, and a burner disposed at the bottom of the back wall and so arranged that the flames therefrom will rise between the back wall and front member.

4. A stove comprising a back wall member, a front plate secured to the front thereof, and comprised of a plurality of contiguous rounded vertically extending columns, each column having a grille therein, means for holding the front plate in proper spaced relation to the back wall and forming a plurality of vertical flues between the front plate and back wall, and a burner at the bottom thereof arranged in such manner that the flames therefrom will pass upwardly through the flues between the front plate and the back wall.

5. A stove comprising a back wall member, an integral front cover member, a plurality of vertically extending projections formed on one of said members for holding the front cover member and back wall in spaced relation, and providing vertical flues between the grid and back wall, said front cover member having openings therein, and a burner disposed at the lower part of the stove arranged in such manner that the heat and flames therefrom may pass upwardly between the front cover member and back wall.

6. A stove comprising an integral cast iron body member forming a back wall, sides, and base, and having ribs on the back wall thereof, an integral front cover member detachably secured to the body member and held in spaced relation thereto by means of said ribs, thereby forming a plurality of vertical flues, said front cover member having openings arranged therein in such manner that parts of the interior of each flue is visible, a burner disposed at the base of the stove and so arranged that the flames therefrom may pass upwardly between the front cover member and back

- wall, and a sheet metal casing at the back of the back wall and spaced therefrom.
7. A stove comprising a back wall member having a plurality of holes therein, a front cover member secured to the front thereof and having grilles therein, means holding the grid and back wall in spaced relation, and a plate at the rear face of the back wall having projections thereon extending through the openings into the space between the back wall and front cover member, and a burner at the bottom of the stove so arranged that the heat and flames therefrom will pass upwardly between the front cover member and back wall.
8. A stove comprising an integral back wall having a plurality of holes therein, a front cover member having openings therethrough secured to the front face of the back wall, means on one of said members for holding them in spaced relation and for dividing the intervening space into a plurality of vertical flues, a burner at the bottom of the back wall so arranged that the flames therefrom will go upwardly into said flues, and a metal plate on the rear face of the back wall having projections thereon extending through said holes in the back wall into the flues.
9. The combination with a stove having a back wall, of a front cover member in the form of an integral plate secured in front thereof, said front cover member having grilles therein, and vertically extending ribs for holding the front cover member in spaced relation to the back wall.
10. The combination with a stove having a back wall, of a front cover member secured to the front face thereof comprising an integral metal body having a series of vertically arranged grilles therein, and cooperating parts on the front cover member and back wall for holding the front cover member in spaced relation to the back wall and providing a series of vertically extending flues in the intervening space, the fronts of said flues being comprised of the grille portions of the front cover member.

In testimony whereof we affix our signatures.

EMANUEL B. ADLER.
JEROME ADLER.
